UNITED STATES PATENT OFFICE.

ROBERT O. HODGE, OF BUFFALO, NEW YORK, ASSIGNOR, BY DIRECT AND MESNE ASSIGNMENTS, TO DIAMOND POWER SPECIALTY COMPANY, OF DETROIT, MICHIGAN, A CORPORATION OF MICHIGAN.

BOILER-TUBE CLEANER.

1,065,527.

Specification of Letters Patent. Patented June 24, 1913.

Application filed November 15, 1909. Serial No. 528,260.

To all whom it may concern:

Be it known that I, ROBERT O. Hodge, a citizen of the United States, residing at Buffalo, in the county of Erie and State of New York, have invented new and useful improvements in Boiler-Tube Cleaners, of which the following is a specification.

This invention relates to that class of boiler tube or flue cleaners in which the cleaning effect is produced by directing steam toward a part of the flue area at a time and successively over the different parts of the flue area so as to concentrate the steam pressure and obtain the maximum cleaning effect of the same.

It has been found in practice that the greatest efficiency of the steam is obtained for cleaning the tubes when the steam is delivered directly or nearly so from the supply device into the tubes, inasmuch as the steam when thus delivered does not materially lose its force by the time it strikes the tubes.

One of the objects of this invention is to produce a tube cleaner of this character which permits of directing the steam at close range successively into the different tubes or flues of the boiler and in a direction lengthwise thereof or nearly so.

Another object of this invention is the production of a flue cleaner having this capacity which operates equally effective on the tubes at the outer or marginal part of the tube area and the tubes at and near the center of this tube area, thus rendering the same particularly desirable for use in boilers having a very large flue area.

My invention has the further object to provide a tube cleaner which is capable of delivering steam at close range and substantially lengthwise into the several flues and which is capable of retraction out of the combustion chamber when not in use so that the cleaner will not be burned or worn uniformly by the heat of the furnace.

In the accompanying drawings: Figure 1 is a fragmentary vertical longitudinal section of the rear part of a boiler and the rear wall of the combustion chamber in connection with my improved tube cleaner. Fig. 2 is a vertical longitudinal section, on an enlarged scale, of my improved tube cleaner showing the parts in the position which they occupy when the cleaner is in use. Figs. 3,

4 and 5 are cross sections, on an enlarged scale, in the correspondingly numbered lines in Fig. 2. Fig. 6 is a fragmentary longitudinal section in line 6—6, Fig. 7. Fig. 7 is a vertical cross section, on an enlarged scale, in line 7—7, Fig. 2. Fig. 8 is a fragmentary longitudinal section, on an enlarged scale, showing a modification of the means for retracting the steam delivery nozzle.

Similar letters of reference indicate corresponding parts throughout the several views.

Although my improved tube cleaner is applicable to various forms of boilers and settings that shown in the drawings, as an example, comprises a body A which is provided at its rear end with a head or flue sheet a; a plurality of horizontal tubes or flues b extending at their rear ends through the tube sheet and opening into the combustion chamber or heat passage B in rear of the boiler, and an upright rear wall C forming the back of the combustion chamber. As shown in the drawings, this wall is constructed of brick and forms part of the boiler setting as is usual in the case of stationary boilers but in marine boilers this wall usually forms part of the boiler itself and constitutes the rear water leg thereof.

The preferred embodiment of my invention which is shown in the drawings is as follows:—D represents the outer stationary shell or casing of the cleaner which is preferably constructed in the form of a tube which is arranged horizontally within an opening in the rear wall of the combustion chamber so that its inner end extends nearly to the front side of this wall and its rear or outer end projects outwardly or rearwardly from the rear side of this wall. This tubular casing is arranged parallel with the tubes or flues of the boiler and opposite the center of the area of the tubes or flues which are to be cleaned. At its front or inner end the tubular casing is provided with an internal annular flange d forming a rearwardly facing internal shoulder d¹ at this end of the bore of the casing. The outer end of the casing is closed by means of a cap E which is preferably removably secured to the casing by means of an external screw thread formed on the cap and engaging with an internal screw thread on this end of the cas-

ing. Steam is admitted to the casing at the outer or rear end thereof by means of a supply pipe F which connects with a laterally projecting nipple f on the outer end of the casing and which is provided with a hand valve f¹ whereby the steam may be turned on for operating the cleaner and turned off when the cleaning operation has been completed.

- 10 Within the shell or casing is arranged an outer or rear carrier section which preferably has the form of a tubular body G arranged lengthwise within the casing and projecting at its front end forwardly 15 through the opening formed by the bore of the front flange d on the casing. A skeleton or open work coupling head is arranged on the rear end of the rear carrier section the same consisting preferably of an outer 20 coupling ring H secured by a screw joint to the outer end of the rear carrier section, a central hub h arranged rearwardly of the ring H, and inclined arms h¹ connecting the hub and rings and forming steam passages 25 between the same whereby the interior of the shell or casing and the interior of the rear carrier section are placed in communication with each other. The front end of the rear carrier section is reduced forming a forwardly projecting shoulder g on the periphery of this end of the carrier which bears against the rearwardly facing shoulder d¹ of the shell, and the rear end of the hub of the coupling head bears against the inner or 30 front side of the rear head of the shell, thereby confining the rear carrier section against lengthwise or axial movement in the shell but permitting rotary movement of the same therein for a purpose to be 35 hereinafter mentioned. The front head g¹ of the rear carrier section is preferably formed integrally with this section and is arranged obliquely with reference to its axis of rotation.
- 40 I represents a front or inner carrier section which is of hollow or tubular form and which is capable of sliding lengthwise 45 through an opening i in the front head g¹ of the rear carrier section for the purpose 50 of protecting or extending the front section forwardly beyond the rear section when the cleaner is in use or withdrawing the front section rearwardly into the rear section so that its front end is nearly flush with the 55 front end of the rear section when the cleaner is not in use. By means of this telescopic connection between the front and rear sections of the carrier the same can be extended for delivering the steam close to 60 the ends or mouths of the tubes or flues to be cleaned and to be contracted or shortened so that the front carrier section is withdrawn from the heat passage within the combustion chamber. The opening i is arranged on one side of the axis of the rear

carrier section and in the rearmost part of the head g¹. The front carrier section is preferably curved and arranged so that its inner or concave side faces rearwardly or toward the innermost end of the inclined head g¹ on the front end of the rear carrier section, the front and rear carrier sections being retained in this relative position, preferably, by providing opposite sides of the front carrier section with flat parallel longitudinal faces j which engage with correspondingly shaped faces j¹ on the adjacent part of the bore of the opening i in the front end or head of the rear carrier section. In its projected position the rear end of the front carrier section is arranged at substantially right angles to the oblique head g¹ at the front end of the rear section, whereby the front end of the latter is caused to project laterally with reference to the axis 85 of rotation of the rear carrier section.

The rotary movement of the carrier sections may be effected by various means but preferably by the means shown in the drawings which consist of an outer hollow or tubular shaft K extending lengthwise through a stuffing box k arranged centrally on the outer head of the casing and connected at its front end with the hub of the coupling head of the rear carrier section, and a crank 90 or handle k¹ secured to the rear or outer end of this hollow shaft.

Various means may be provided for moving the front carrier section into and out of the rear carrier section but the means shown in the drawings are preferred and are constructed as follows: L represents a screw ring having an external thread engaging with the internal thread of the rear carrier section and provided in its bore with a 105 spherical socket which receives a hollow spherical knuckle or ball l. The rear side of this knuckle is open for the admission of steam from the rear carrier section and its front side is provided with a steam outlet 110 nipple l¹ which opens into the outer end of the front carrier section and is connected therewith by a screw joint. To permit of inserting the knuckle into the spherical socket of its screw ring and the removal of 115 the same therefrom one half of this socket in front of the center of the joint is formed by an internal integral flange l² on the front part of the screw ring while the rear part of this socket is formed by a sleeve l³ which is 120 secured by a screw joint in the rear part of the bore of this screw ring, the two parts being preferably held against turning relatively to each other when the cleaner is assembled by means of a radial screw l³, as 125 shown in Fig. 4, or by any other suitable means. Upon turning the screw ring in one direction, the front carrier section and the parts connected therewith are moved rearwardly relatively to the rear carrier section 130

while upon turning the screw ring in the opposite direction the front carrier section and the parts connected therewith are moved in the opposite direction relatively to the rear carrier section. The screw ring may be thus turned for changing the relative position of the parts mentioned by any suitable means but preferably by the means shown in the drawings which comprise a hub m arranged centrally in front of the screw ring and connected with the removable sleeve thereof by means of inclined arms m^1 , a hollow inner shaft M extending lengthwise through the hollow outer shaft K of the rear carrier section and a stuffing box m^2 at the rear end of the latter and connected at its front end with the hub m , a cap N secured to the rear end of the inner hollow shaft, and a crank or handle n secured to the rear side of said cap. Upon turning the crank n in one direction or the other the shifting screw ring is caused to move either forward or backward in the rear carrier section and either project or retract the front carrier section connected therewith. The forward movement of the front carrier section is preferably limited by means of a shoulder o formed on the exterior of the front carrier section at the rear end thereof and engaging with the rear side of the oblique front head g^1 of the rear carrier section, as shown in Fig. 2. The backward or rearward movement of the screw ring and the parts connected therewith may also be limited by various means but preferably by engagement of the rear end of the hub of this ring with the front end of the hub of the rear carrier section, as shown by dotted lines in Fig. 2.

P represents a nozzle whereby the steam is delivered from the front carrier section into the mouths or open inlet ends of the boiler tube or flues. This nozzle is preferably constructed in the form of a curved tube which is concentric with the curved front carrier section and is capable of being projected and retracted with reference to the front carrier section so as to bring the steam outlet of the nozzle close to the ends of the tubes when the cleaner is in use and to retract the nozzle out of the heat passage when the cleaner is not in use. For this purpose the nozzle is mounted on the front carrier section so as to be capable of a telescopic movement forwardly and rearwardly into and out of the same, this being effected by extending the nozzle through an opening p at the front end of the front carrier section and giving the same a curvature corresponding to that of the front carrier section. The forward movement of the nozzle is preferably effected by means of the steam pressing against the rear end of the same which movement is limited by means of an external forwardly facing shoulder p^1 arranged on the rear end of the nozzle and engaging with an internal

rearwardly facing shoulder p^2 at the front end of the front carrier section, as shown in Fig. 2. The turning movement of the nozzle and the front carrier section relatively to each other is preferably prevented by means of cooperating flat faces q , q^1 on opposite longitudinal sides of the nozzle and on opposite sides of the bore of the front opening in the front carrier section, as shown in Fig. 5, thereby retaining the nozzle and front carrier section always in a concentric position relatively to each other.

At its front end and projecting forwardly therefrom the nozzle is provided with a front steam delivery nipple r and in rear of this front nipple and on the convex side thereof the nozzle is provided with an additional rear or auxiliary steam delivery nipple r^1 . These two nipples diverge forwardly and preferably at such an angle relatively to each other that in the foremost projected position of the nozzle and front carrier section the front nipple r inclines forwardly and laterally while the rear nipple r^1 is arranged parallel with the axis of rotation of the carrier.

The backward movement of the nozzle is limited by engagement of its rear end with the nipple l^1 of the ball and socket joint and this movement may be effected by various means two of which are shown in the drawings. One of these effects the retraction of the nozzle automatically when the steam is turned off while the other permits of retracting the nozzle manually. The automatic nozzle retracting mechanism shown in Figs. 1-7 comprises a return wire, cable, cord or other flexible member S which is secured at its front end to an arch s at the rear end of the nozzle and passes from thence rearwardly through the front carrier section, the hollow knuckle thereof, and through a guide opening t formed in a guide bar or cross piece T within the knuckle, thence rearwardly through the inner hollow shaft and through an opening t^1 in the cap at the rear end thereof, and thence around a drum U journaled on a bracket u secured to or mounted on the cap N . When the nozzle is projected by steam pressure upon opening the valve f^1 preparatory to cleaning the tubes, a spring V is strained, which spring is preferably of the coil type and secured at one end to the shaft of the drum U while its opposite end is secured to the handle n or adjacent part turning therewith, so that when the wire or cable is unwound from the drum the spring V will be wound up and put under tension. The instant the steam pressure is turned off from the nozzle by the closing of the valve f^1 the resilience of the spring V causes the drum U to turn in the reversed direction in which it winds the cord or cable upon the drum and draws the nozzle rearwardly into the front carrier section.

The manual means for effecting the return of the nozzle into the front carrier sections, which are shown in Fig. 8, consist in providing the rear end of the wire, cable or cord 5 S with a handle or loop s^1 which may be grasped by the hand for withdrawing the nozzle after the steam has been turned off.

When the tube cleaner is not in use the nozzle is drawn backwardly to its fullest extent into the front carrier section and the latter together with the nozzle is moved backwardly to its fullest extent in the rear carrier section, as shown in full lines in Fig. 1, in which position of the parts the front 10 ends of the front carrier section and nozzle are almost wholly withdrawn from the path of the heat thus reducing burning of the same to a minimum. When it is desired to clean the boiler tubes, the valve f^1 is opened 15 whereby the steam enters the casing and carrier sections and by its pressure pushes the nozzle forwardly in the front carrier section to the fullest extent and the steam issues forwardly from the front and rear nipples of 20 the nozzle. Upon now turning forwardly the handle n connected with the inner shaft of the front carrier section, the latter together with the nozzle will be moved forwardly in the rear carrier section and also 25 laterally relatively thereto owing to the guide opening in the front head of the rear carrier section being on one side of the axis of the same. By this means the steam delivery nipples of the nozzle are shifted radially and successively opposite different 30 circular groups of the tubes of the tube area, so that upon turning the nozzle and carrier sections by means of the handle h^1 the steam issuing forwardly from the nipples 35 will be directed successively into the mouths or inlet ends of the tubes or flues of the several concentric groups or series.

In the foremost position of the nozzle in which the same is also projected farthest laterally from the axis of rotation of the carrier, the front nipple r is close to the inlet ends of the outermost tubes of the tube area so that the steam is delivered into the same under high pressure, thereby obtaining 45 the greatest cleaning efficiency of the steam on the tubes. The position of the front and rear nipples on the nozzle is such that when the front carrier section is in its rearmost position and the nozzle is projected its fullest extent by the steam pressure, the steam will be directed by the rear nipple r^1 at an angle into the central tubes of the tube area and at comparatively close 50 range relatively to the same, and steam is also delivered by the front nipple r into those tubes arranged at one side of the central tubes, the front nipple at this time being arranged still closer to the tubes mentioned and delivering the steam into the 55 same in a direction parallel with the length

of said tubes, as shown by dotted lines in Fig. 1. As the front carrier section is moved forwardly together with the projected nozzle, the front and rear nipples both move closer to the ends of the flues or tubes and also outwardly relatively to the center of the flue area. During this forward and outward movement of the nozzle the angles of its nipples relatively to the plane of the flue sheet change constantly 70 and when the nozzle reaches the limit of its forward and outward movement the front nipple is arranged close to the outer flues and projects forwardly and outwardly at an angle relatively to said flues, as shown by full lines in Fig. 2, whereby the steam issuing from this nipple is delivered at close range and at an angle into these tubes and the rear nipple is arranged parallel with the flues and also delivers the steam issuing therefrom at comparatively close range and lengthwise into the intermediate flues of the flue area. By this means the steam acts on the flues under high pressure and before it has partly spent itself, as occurs when the steam is projected through a space of considerable length before striking the tubes, thereby enabling the flues to be cleaned quickly, thoroughly and economically.

By curving the nozzle and the front section of the carrier in the manner shown the steam delivery nipples r , r^1 during their lateral movement are retained close to ends of the tubes much longer than if the nozzle and front carrier section were made straight, inasmuch as a structure like that last mentioned would cause the nipples to advance and recede abruptly relatively to the ends of the boiler tubes instead of moving past the same in a curve as in the present construction.

My improved tube cleaner is particularly desirable for use in large boilers inasmuch as it permits of cleaning the outermost flues as effectively as the flues nearer the center 110 of the flue area, thereby avoiding the necessity of cleaning such outer flues by hand.

I claim as my invention:

1. The combination of a casing adapted to be secured within a wall, a carrier rotatably arranged in said casing, a curved steam-delivery nozzle slideable into and out of said carrier, means for movably connecting the nozzle with the carrier, and means for supplying steam to the nozzle.

2. A boiler tube cleaner comprising a rotatable carrier having a steam inlet and composed of a tubular rear section, a tubular front section slideable on the rear section at an angle to the axis of the latter, and a steam delivery nozzle slideable lengthwise on the front carrier section.

3. A boiler tube cleaner comprising a stationary casing having a steam inlet, a carrier having a tubular rear section which is

rotatable in said casing but immovable lengthwise relatively thereto and a tubular front section which turns with the rear section but is slideable relatively thereto at an 5 angle to the axis of rotation; and a steam delivery nozzle slideable lengthwise on said front carrier section.

4. A boiler tube cleaner comprising a stationary casing having a steam inlet, a carrier having a tubular rear section which is 10 rotatable in said casing but immovable lengthwise relatively thereto and a curved tubular front section which turns with the rear section but is slideable relatively thereto at an angle to the axis of rotation, and a curved steam delivery nozzle slideable lengthwise on said front carrier section.

5. A boiler tube cleaner comprising a stationary casing having a steam inlet, a carrier having a tubular rear section which is 20 rotatable in said casing but immovable lengthwise relatively thereto and a curved tubular front section which turns with the rear section but is slideable relatively thereto at an angle to the axis of rotation, and a curved steam delivery nozzle slideable lengthwise on said front carrier section, said carrier sections and nozzle being constructed to prevent relative rotation of these 30 parts.

6. A boiler tube cleaner comprising a stationary casing having a steam inlet, a carrier having a tubular rear section which is 35 rotatable in said casing but immovable lengthwise relatively thereto and a tubular front section which turns with the rear section but is slideable relatively thereto at an angle to the axis of rotation, and a steam delivery nozzle slideable lengthwise on said 40 front carrier section, said nozzle being provided on its front side with a delivery nipple at its end and another delivery nipple at a distance from its end.

7. A boiler tube cleaner comprising a stationary casing having a steam inlet, a carrier having a tubular rear section which is 45 rotatable in said casing but immovable lengthwise relatively thereto and a tubular front section which turns with the rear section but is slideable relatively thereto at an angle to the axis of rotation, and a steam delivery nozzle slideable lengthwise on said 50 front carrier section, said nozzle being provided on its front side with a delivery nipple at its end and another delivery nipple at a distance from its end, said nipples diverging forwardly.

8. A boiler tube cleaner comprising a stationary casing having a steam inlet, a carrier having a tubular rear section which is 60 rotatable in said casing but immovable lengthwise relatively thereto and a tubular front section which turns with the rear section but is slideable relatively thereto at an 65 angle to the axis of rotation, a steam deliv-

ery nozzle slideable lengthwise on said front carrier section, and means for limiting the forward movement of said front carrier section on the rear carrier section and the nozzle on the front carrier section.

9. A boiler tube cleaner comprising a rear rotatable tubular carrier section having a steam inlet, a front tubular carrier section movable lengthwise relatively to said rear section, a nozzle on said front section, and means for moving said front section comprising an externally screw threaded ring 70 engaging with an internal thread in said rear carrier section and connected with said front carrier section.

10. A boiler tube cleaner comprising a stationary casing having a steam inlet, a tubular carrier having a rear section rotatable in said casing and a front section slideable lengthwise relatively to the rear section, a hollow outer shaft extending through the front end of said casing and connected with said rear carrier section, a screw ring 80 engaging with a thread on said rear section and connected with the front section, and an inner shaft arranged within the outer shaft and connected with said screw ring.

11. A boiler tube cleaner comprising a stationary casing having a steam inlet, a 95 tubular carrier having a rear section rotatable in said casing and a front section slideable lengthwise relatively to the rear section, a hollow outer shaft extending through the front end of said casing and connected with said rear carrier section, a screw ring 100 engaging with a thread on said rear section and connected with the front section, an inner shaft arranged within the outer shaft and connected with said screw ring, and handles arranged on the outer ends of said shafts.

12. A boiler tube cleaner comprising a tubular carrier having a steam inlet and rear rotatable section and a front section rotatable with the rear section and movable lengthwise of the rear section at an angle to the axis of rotation, a steam delivery nozzle mounted on the front carrier section, and means for moving the front carrier section comprising a screw ring engaging with a thread in the rear carrier section and having a spherical socket, and a hollow spherical knuckle connected with the front carrier section and seated in said socket.

13. A boiler tube cleaner comprising a tubular carrier having a steam inlet and rear rotatable section and a front section rotatable with the rear section and movable lengthwise of the rear section at an angle to the axis of rotation, a steam delivery nozzle mounted on the front carrier section, and means for moving the front carrier section comprising a screw ring engaging with a thread in the rear carrier section and hav-

- ing a spherical socket, a hollow spherical knuckle connected with the front carrier section and seated in said socket, a casing in which said rear carrier section is journaled and which is provided with a steam inlet, an outer hollow shaft connected with said rear carrier section and extending through the casing, and an inner shaft connected with said screw ring and extending through said outer hollow shaft.

14. A boiler tube cleaner comprising a tubular carrier having a steam inlet, a steam delivery nozzle slidable lengthwise of said carrier and adapted to be moved forward by the pressure of the steam, and a retracting member connected with said nozzle.

15. A boiler tube cleaner comprising a tubular carrier having a steam inlet, a steam delivery nozzle slidable lengthwise of said carrier and adapted to be moved forward by the pressure of the steam, and means for moving said nozzle rearwardly comprising a flexible member connected with said nozzle and extending through said carrier.

16. A boiler tube cleaner comprising a tubular carrier having a steam inlet, a steam delivery nozzle slidable lengthwise of said carrier and adapted to be moved forward by the pressure of the steam, and means for moving said nozzle rearwardly comprising a flexible member connected with said nozzle and extending through said carrier and a drum upon which said flexible member is wound.

17. A boiler tube cleaner comprising a tubular carrier having a steam inlet, a steam delivery nozzle slidable lengthwise of said carrier and adapted to be moved forward by the pressure of the steam, and means for moving said nozzle rearwardly comprising a flexible member connected with said nozzle and extending through said carrier, a drum upon which said flexible member is wound, and a spring operating to turn said drum in a direction for winding the flexible member thereon and retracting the nozzle.

18. A boiler tube cleaner comprising a tubular carrier having a steam inlet and a rear rotatable section and a front section rotatable with said rear section and movable lengthwise of the latter at an angle to the axis of rotation, a steam delivery nozzle slidable lengthwise of the front carrier section, means for moving said front carrier section lengthwise comprising a hollow shaft, and means for drawing said nozzle rearwardly comprising a flexible member connected with the nozzle and passing through said carrier sections and shaft.

19. A boiler tube cleaner comprising a tubular carrier having a steam inlet and a rear rotatable section, and a front section rotatable with said rear section and movable lengthwise of the latter at an angle to the axis of rotation, a steam delivery nozzle

20. A boiler tube cleaner comprising a tubular carrier having a steam inlet and a rear rotatable section, and a front section rotatable with said rear section and movable lengthwise of the latter at an angle to the axis of rotation, a steam delivery nozzle slidable lengthwise of the front carrier section, a stationary casing in which said rear carrier section is journaled, means for turning said rear carrier section comprising an outer hollow shaft extending through the rear end of said casing and connected with said rear carrier section, means for moving said front carrier section rearwardly comprising a screw ring engaging with a screw thread in the bore of the rear carrier section, a hollow spherical knuckle connected with said front carrier section and seated in a correspondingly shaped socket in said screw ring and an inner hollow shaft extending through said outer hollow shaft and connected with said screw ring, and means for moving said nozzle rearwardly comprising a flexible member connected with said nozzle and extending through said carrier sections and shafts.

21. A boiler tube cleaner comprising a tubular carrier having a steam inlet and a rear rotatable section, and a front section rotatable with said rear section and movable lengthwise of the latter at an angle to the axis of rotation, a steam delivery nozzle slidable lengthwise of the front carrier section, a stationary casing in which said rear carrier section is journaled, means for turning said rear carrier section comprising an outer hollow shaft extending through the rear end of said casing and connected with said rear carrier section, means for moving said front carrier section rearwardly comprising a screw ring engaging with a screw thread in the bore of the rear carrier section, a hollow spherical knuckle connected with said front carrier section and seated in a correspondingly shaped socket in said screw ring and an inner hollow shaft extending through said outer hollow shaft and connected with said screw ring, and means for moving said nozzle rearwardly comprising a flexible member connected with said nozzle and extending through said carrier sections and shafts, and a guide for said flexible member arranged in said knuckle.

22. A boiler tube cleaner comprising a tubular carrier having a steam inlet and a rear rotatable section, and a front section rotatable with said rear section and movable lengthwise of the latter at an angle to the axis of rotation, a steam delivery nozzle slidable lengthwise of the front carrier section, a stationary casing in which said rear carrier section is journaled, means for turning said rear carrier section comprising an outer hollow shaft extending through the rear end of said casing and connected with said rear carrier section, means for moving said front carrier section rearwardly comprising a screw ring engaging with a screw thread in the bore of the rear carrier section, a hollow spherical knuckle connected with said front carrier section and seated in a correspondingly shaped socket in said screw ring and an inner hollow shaft extending through said outer hollow shaft and connected with said screw ring, and means for moving said nozzle rearwardly comprising a flexible member connected with said nozzle and extending through said carrier sections and shafts, and a guide for said flexible member arranged in said knuckle.

carrier section and seated in a correspondingly shaped socket in said screw ring and an inner hollow shaft extending through said outer hollow shaft and connected with 5 said screw ring, and means for moving said nozzle rearwardly comprising a flexible member connected with said nozzle and extending through said carrier sections and shafts, a guide for said flexible member arranged in said knuckle, a drum mounted on the rear end of said inner shaft and receiving said flexible member, and a spring connected with said drum and adapted to be strained by the forward movement of the 15 nozzle.

22. The combination of a casing adapted to be secured within a wall, a tubular section slidable within said casing, and means connecting said section and casing adapted 20 to permit the section to turn out of longitudinal alignment with the casing as said section is projected therefrom.

23. The combination of a casing adapted to be secured within a wall, a section adapted 25 to be retracted within and extended from said casing, and means jointedly connecting said section and casing and adapted to permit the section to move out of longitudinal alignment with the casing.

30 24. The combination of a casing adapted to be secured within a wall, of a plurality of sections telescopically connected together, and said sections in their retracted positions being housed within the casing, the 35 inclosing one of said sections being rotatably supported in the casing and connected thereto to permit of turning the inclosing section at an angle to said casing.

25. The combination of a casing adapted

to be secured within a wall, of a plurality 40 of sections adapted to be housed one within another and within the casing and rotatably supported within the latter, one of the rotatable sections being connected to the casing and adapted to permit a turning thereof at 45 an angle in relation to the said casing.

26. The combination of a casing adapted to be secured within a wall, of a plurality of sections retractable one within another, the inclosing one of said sections being rotatably supported within the casing and pivotally connected to the casing and adapted to permit of a turning at an angle in relation to the casing.

27. The combination of a casing adapted 55 to be secured within a wall, of a plurality of sections in telescopic relation with one another and retractable within the casing, the inclosing section being rotatably supported in the casing and connected to the 60 casing and adapted to permit a turning of the inclosing section at an angle to the casing.

28. The combination with a casing adapted to be secured within a wall, of a plurality 65 of telescopically connected sections revolvably supported in said casing and adapted to be housed within the same in their retracted positions, and means jointedly connecting said sections with the casing and 70 free to turn at an angle to the casing when extended.

Witness my hand this 8th day of November, 1909.
